CHARLES M. DUMOND, OF WATERLOO, IOWA.

ACTUATING MECHANISM FOR WASHING-MACHINES.

1,081,726.

Specification of Letters Patent. Patented Dec. 16, 1913.

Application filed August 16, 1912. Serial No. 715,434.

To all whom it may concern:

Be it known that I, CHARLES M. DUMOND, a citizen of the United States of America, and a resident of Waterloo, Blackhawk county, Iowa, have invented certain new and useful Improvements in Actuating Mechanism for Washing-Machines, of which the following is a specification.

My invention relates to improvements in actuating mechanism for washing machines or the like, and the object of my improvement is to provide a simple, inexpensive and easily operative mechanism for imparting a simultaneous rocking and translatory movement to a plunger-rod, without binding or complexity of parts, or difficulty in repair. This object I have accomplished by the mechanism which is hereinafter described and claimed, and which is illustrated 20 in the accompanying drawings, in which:

Figure 1 is an end elevation of my said mechanism as applied to the tub of a washing machine, said tub being vertically and centrally sectioned and partly broken away.

Fig. 2 is a detail side elevation of my improved actuating mechanism. Fig. 3 is a detail perspective view of the conjoint swiveled and hinged connection between the crank arm and the slide-bar of my device.

Fig. 4 is another perspective detail of the parts shown in Fig. 3, but taken from another point of view. Fig. 5 is an enlarged horizontal section through the plunger-rod and its sleeve-bearing for said slide-bar, and 35 also through the crank-arm at the location of its swiveled connection to said slide-bar.

Similar numerals of reference denote corresponding parts throughout the several views.

My improved actuating mechanism for imparting simultaneous translatory and rocking movements to a plunger-body, is shown as applied to use in operating a washing-machine, but it is obvious that said mechanism may be applied to any other use desired.

The numeral 5 denotes the tub of a washing-machine, having a hinged cover 15, on whose top is centrally mounted a bearing-body 4 which has spaced apart bearings for a vertical plunger-rod 1, the lower end of said rod within said tub having a plunger-head 6 secured thereon. Secured upon said plunger-rod above said cover is a sleeve

2 having oppositely-directed horizontal projections, and said rod, sleeve and its projections are horizontally transversely orificed in line to provide a continuous and relatively long bearing-seat for the horizontal slide-bar 3, which last is movable therethrough but never entirely leaves its seat. Mounted also upon said cover 15 are the standards 11 with integral bearings at their upper ends for a crank-shaft 9, which last has thereon a fly-wheel 10 provided with a crank-handle for manual operation. The inner end of said shaft has a crank 8 orificed transversely to rotatably receive the cylindrical connecting body 7, as a swivel, said part 7 having a fork connected by a pindle 13 on which one end of the slide-bar 3 is hinged pivotally. The sleeve 2 is secured on the plunger-rod 1 by means of machine-screws 14 or other suitable means. It will be observed that the upper part of the slide-bar 3 is flattened at 12, this flattened part fits a similar flattened part of the wall of the bearing in the sleeve 2 and rod 1, and prevents the bar 3 from turning.

To operate the device, the shaft 9 is rotated by the means shown or otherwise, to rotate the crank 8, and the crank carries about the pin on the body 7, rotating relatively to said pin, while the body 7, its hinge to the slide-bar 3 and said bar 3 remain horizontal and without rotating. Since the slide-bar 3 is carried about by said crank, its outer hinged end swings to cause the inner end to raise and lower the plunger-rod 1, and the said bar 3 simultaneously slides back and forth horizontally through its seat in the bearing orifice in the rod 1 and its sleeve 2. In so sliding to and fro the said bar 3 imparts a rocking movement to said plunger-rod. Thus a simultaneous translatory and rocking movement is impressed upon said rod.

Having described my invention, what I claim as new, and desire to secure by Letters Patent, is:

1. In combination, a plunger-rod having a transverse orifice, a bearing for said rod, and means adapted to actuate said rod, comprising a rotary crank-shaft, a bar slidable through the orifice in said rod, and a connecting body having one end hinged to the adjacent end of said slide-bar and its other end swiveled to the crank on said shaft.

2. In combination, a plunger-rod, a sleeve secured thereon and having integral oppositely-directed parts, said parts, the sleeve and the rod being transversely orificed, a slide-bar slidably mounted in the seat in said parts, a rotary crank-shaft, and a body hinged to one end of said slide-bar and swiveled to the crank on said shaft, and

adapted to impart simultaneous translatory and rocking movements to said plunger-rod. 10

Signed at Waterloo, Iowa, this 2nd day of August, 1912.

CHARLES M. DUMOND.
